AARON M. HAGEMAN, OF BLOOMFIELD, AND ALBERT F. LINDSTROM, OF NUTLEY, NEW JERSEY, ASSIGNORS TO WESTINGHOUSE LAMP COMPANY, A CORPORATION OF PENNSYLVANIA

METHOD AND APPARATUS FOR COATING THE INTERIOR WALL OF HOLLOW BODIES

Application filed December 9, 1927. Serial No. 238,734.

This invention relates to the method of coating hollow bodies and more particularly to the coating of glass or vitreous articles such as incandescent electric lamp bulbs or 5 the like.

In the manufacture of incandescent electric lamps, it is important to be able to provide a bulb, which is made either of a light diffusing vitreous material or of a clear glass bulb 10 having a coating of a light diffusing character and at the same time, obtain a maximum light efficiency. It has been proposed to obtain light diffusing effects by the employment of a so-called opalescent or opal glass. The opalescent effect being attained by adding cryolite to a batch of glass during manufacture. This was an expensive procedure and furthermore, such glass acts to decompose liberating 15 gases, probably silicon-fluoride which are detrimental to the filament and shorten the life of the lamp. Furthermore, the light absorption by reason of opal glass is extremely high and inasmuch as it is not possible to obtain a uniform thickness of a bulb, the resultant transmitted light varied in intensity. 20

The nearest approach to the opalescent effect in connection with coated lamps was attained by the application of a coating to the outer surface of the bulb such, for example, 25 as that set forth in Patent 1,613,758 January 11, 1927.

The outside coating of bulbs, however, although giving a satisfactory light diffusing medium, did not attain the desired opalescent 30 effect which may be defined as a light diffusing medium enclosed in a glossy or highly polished surface as the exterior surface of a lamp bulb. It has been proposed to etch the inside surface of a lamp bulb with an acid 35 such as a hydrofluoric acid or other etching solution. This method physically changes the inner surface of the bulb, breaking the same into numerous minute hills and valleys which reflect light at all angles and cause a 40 diffusion of the emitted light. The etched surface, however, did not answer the requirement of producing a desirable opalescent effect, since the intensity of a lamp filament is 45 too great to be diffused uniformly by the roughened surface of the bulb and although 50

the transmitted light was diffused to an appreciable degree, a concentrated spot of light always remained visible. Furthermore, the etching of a bulb by means of acid required the exercise of extreme care, since the acid 55 fumes were deleterious to the workers and extreme caution was necessary in performing the etching operation.

The present invention aims to provide a lamp bulb with a light diffusing coating so 60 arranged that the coating in combination with the smooth exterior surface of the bulb gives the desired opalescent or pearly effect.

As set forth in our copending application Serial No. 737,609 filed September 13, 1924 65 for coated article and method of making the same, the desired opalescent effect is attained by applying a light diffusing material to the inside surface of a lamp bulb and it is an object of the present invention to provide a method and apparatus whereby such material may be applied in a convenient and expeditious manner. 70

Another object of the invention is to provide a method of coating the inside surface 75 of a hollow transparent body with a uniform light diffusing layer.

Another object of the invention is to produce a lamp bulb comprising a uniform light diffusing layer on the inside surface of a 80 translucent body which layer in combination with the glossy exterior surface of the body, will constitute a light diffusing medium, giving the desired opalescent effect. 85

The smooth outer surface of a lamp bulb or other container provided with a light diffusing inner layer is not only desirable from an ornamental standpoint, but provides an article in which the light diffusing layer is 90 wholly protected from atmospheric conditions or from mechanical abrasion and provides a surface which may be readily cleaned and which will retain its initial lustrous appearance. 95

In the manufacture of bulbs in accordance with the present invention, it has been found that certain novel manipulative steps must be followed so that the coating will have the desired uniformity in order that the coated 100

lamp may have the required depth of color as when using various colored pigments.

The invention is, of course, applicable for the coating of various forms of hollow translucent bodies, but is herein shown and described in connection with the coating of the inner wall of a transparent vitreous incandescent electric lamp bulb.

The above mentioned type of hollow body, 10 namely a lamp bulb, comprises a sphere-like portion terminating in a relatively narrow opening or neck. The application of a coating material to the inner surface of this form of hollow body is extremely difficult, 15 particularly since it is essential to apply the coating in such manner as to have the same of uniform density throughout. In an electric lamp bulb wherein a high temperatured filament is disposed in close relation to the 20 light diffusing wall, it will be appreciated that any variation or defect in the character of the coating will be exaggerated and readily noticeable, giving the bulb an unfinished or defective appearance.

25 In accordance with the present method, therefore, it has been found that by first heating a bulb to a given temperature then applying a finely divided material to the inner surface of the bulb, preferably while the bulb 30 is rotating, a layer of light diffusing material may be uniformly deposited. It has further been found that the coating is best applied when discharged in the form of a spray such as a coniferous discharge from a spray gun 35 nozzle. The discharge is produced within the bulb and directed to a wall thereof, while a relative movement between the bulb and the spray nozzle is effected until the entire surface of the bulb receives a light diffusing 40 layer.

The manipulation of the spray gun is important by reason of the close working relation necessary, inasmuch as the spray nozzle is confined to the space within the bulb. The 45 spray nozzle is introduced into the bulb at an angle to the longitudinal axis of the bulb, after which a discharge of sprayed material is produced. The nozzle is then moved lengthwise of the bulb to direct sprayed material against the surface of the bulb from a point adjacent to the neck thereof to a point at the top of the bulb or the inter-section between the longitudinal axis of the bulb and the wall thereof. A rotation or relative 50 movement of the bulb and spray nozzle during the spraying operation, preferably a rotation of the bulb, results in the deposit of a layer of sprayed material, but as the nozzle moves toward the end of the bulb, the 55 contour of the bulb is such that the distance between the spray nozzle and the bulb decreases, thus a rotation of the bulb causes the surface of the bulb at the narrow portion (or dead center of rotation) near the end to rotate at a less speed than the wider portion.

Normally, therefore, the end of the bulb would receive an excessive amount of sprayed material. To avoid this, the spray is kept from impinging directly upon the end of the bulb and the spray gun is so manipulated that the body portion of the spray coats the inner surface of the bulb up to a point adjacent to the end of the bulb and the roving particles of spray which surround the main body of the discharge are sufficient to cover the upper portion of the bulb with a layer of the same degree of intensity as is deposited upon the other portions of the bulb in the direct path of movement of the spray discharge.

70 After the bulb has been sprayed, it is moved into a baking oven to dehydrate the coating. This baking operation depends, of course, upon the character of coating employed.

75 The present method of coating by the apparatus employed results in a uniform deposit of coating upon the inner wall of a bulb and gives an article having a uniform light diffusing medium which, in combination with the lustrous outer surface of the bulb, provides the desired opalescent effect.

80 The invention will be more fully understood by reference to the accompanying drawings in which:

Fig. 1 is a more or less diagrammatic plan view of an apparatus for practicing the present method;

Fig. 2 is a side elevational view of the apparatus shown in Fig. 1 but with the spray mechanism removed for the sake of clarity;

Fig. 3 is an enlarged plan view of a portion of the machine shown in Fig. 1 and more clearly illustrates the spray gun mechanism;

Fig. 4 shows a bulb in position to be sprayed and with the spray gun about to enter the bulb;

Fig. 5 is a view similar to Fig. 3 which shows the spray gun within the bulb with a discharge of spray projected to the surface of the bulb.

Fig. 6 shows a spray gun in its advanced position within the bulb to spray the upper portion thereof; and,

Fig. 7 is a view showing the spray nozzle in position adjacent to a steam jet for cleaning the nozzle.

An apparatus for practicing the present method may comprise a conveyor 10 provided with an odd number of bulb holders 13. In the present illustration, 37 bulb holders are employed and the conveyor moves intermittently in stages so that every other bulb holder is applied to spraying mechanism. An oven 14 extends about the path of movement of the conveyor so as to receive the moving bulbs 15, to heat the same prior to a spraying operation and also to bake the sprayed bulbs.

The use of the single oven to preheat the bulbs and bake the coated bulbs is accomplished by having the conveyor with an odd number of bulb holders so that after a bulb 5 has been moved adjacent to a spray gun mechanism 16 and a bulb has been sprayed, this bulb will not be removed from the conveyor but will pass through the oven for a baking operation. This is accomplished by having means associated with the conveyor at A which operates to eject a bulb, by means to be later described, from a holder so that the bulb will drop into a chute 17. The mechanism for actuating the holder to release the bulb operates, however, to remove a bulb from every 15 other holder so that a sprayed lamp will only be ejected upon its second application to the said mechanism which causes its ejection from the holder.

20 With this arrangement, it will be evident that as the conveyor moves in the direction of the arrow X a coated lamp and an empty holder will be moved toward the oven 14. Before the empty holder enters the oven 14, 25 however, the operator at B inserts a new bulb into the holder. Since the conveyor indexes for every two bulbs, the bulb which has already been sprayed will pass the spraying mechanism upon the second revolution of the 30 sprayed bulb with the conveyor, this is due to the odd number of bulb holders in the conveyor. The spraying operation is performed by the spray gun 16, which operation will be hereinafter more fully described.

35 During the spraying, it is preferable to rotate the bulbs. For this purpose, each bulb holder may have a shaft 18 supported in bearings 19 on the conveyor 10. These shafts may be disposed radially with respect to the axis 40 of rotation of the conveyor and the end of each shaft may be provided with a pinion 20 positioned to mesh with a gear wheel 21. This gear wheel may be mounted on a shaft 22 and driven by means of a pulley 23 connected with a suitable source of power (not 45 shown).

As the conveyor moves the bulb holders to the spraying position, the pinions 20 will engage with the gear wheel 21, causing a rotation of the bulb. As the conveyor moves each bulb holder away from the spraying position, the pinion 20 will be moved away from the gear wheel, thus terminating the rotation of the bulb holder, although it is 55 evident that if desirable, a series of gear wheels 21 may be provided so that the bulbs may be rotated throughout their movement through the oven.

The foregoing description sets forth the 60 general operation in transporting and positioning the bulbs for the spraying operation. As more clearly shown in Fig. 3, the spray mechanism 16 for spraying the bulb comprises a slide plate 24 upon which is mounted a cross-head 25 for carrying a spray nozzle

26. The spray nozzle may be of any suitable type attached to a tubular portion 27 through which the finely divided spray material is caused to flow. The spray material may enter the tubular portion 27 through a flexible tube 28, which tube, may be connected to a container 29 containing the spray material. The container is usually elevated above the spray gun so that the spray material normally flows by gravity into the spray gun. 70

The discharge of the spray substantially in the form of a fan or cone is effected in the usual manner by the discharge of air which enters a conduit 30 and is directed across a tip 31 of the nozzle 26 by means of an angularly directed outlet orifice 32 as shown in Figs. 5 and 6. This discharge of air passing across the nozzle tip 31 results in the usual ejector effect to atomize and project finely divided material flowing through the tubular passage 27. Means are provided for terminating the flow of coating material except when the nozzle 26 is within the bulb. Such means may comprise a cam 33 which engages a valve 34 to cut off the air flow when the spray gun is in its outer or removed position with respect to a bulb. The cam 33 is actuated upon a movement of the spray gun into the bulb by reason of a lever arm 35 extending from the cam which engages with a pin 36 on a stationary arm 37. Means for moving the nozzle 26 of the spray gun into and out from a bulb 15 may comprise a lever arm 38 which may be rocked in the direction of the arrow Y by any suitable means (not shown). The said arm 38 is provided with a link 39 pivoted at 40 to the cross-head 25. An oscillation of the arm 38, therefore, will cause a movement of the said head with a consequent movement of the spray nozzle 26. 100

In order to properly coat a bulb, it is desirable to move the nozzle into the bulb at an angle to the longitudinal axis of the latter. This is accomplished in the present structure by providing the head 25 with a guide finger 41 movable between angularly disposed tracks 42 and 43. These tracks are arranged to lie beneath the bulb when the same is held in position for spraying. It will thus be evident that as the cross-head is moved toward the bulb, the nozzle 26 will be guided therein. It will be understood that in order to permit a movement of the nozzle and its associated parts in an angular direction in accordance with the tracks 42 and 43, that the said nozzle and the parts thereof must have a pivotal relation with the cross-head 25. The said nozzle is, therefore, pivoted at 44 so that as the cross-head 25 moves to and from the bulb, the nozzle 26 may readily enter the bulb in the direction caused by the guides 42 and 43. 110

As will be noted, the bulb 15 is held in the holder 13 which, as clearly shown in Fig. 3 comprises a pair of jaws 45 and 46 disposed

at the ends of levers 46' and 47. The levers are pivoted on a head 48 slideable on a shaft 49 extending from a hub 50 which is secured to the conveyor 10. At one end of the shaft 5 49 is a jaw 51 and a spring 52 disposed between the jaw and the head 48 serves to normally close the jaws 45 and 46 to grip a bulb. When the conveyor is in position to eject a bulb, an extension 53 on the head 48 engages 10 a suitably positioned cam member 54 causing the head to move toward the bulb and release the same. The above described mechanism for holding and discharging a bulb is given as an example, but it is obvious that 15 this operation may be performed by various forms of mechanism.

In the coating of lamp bulbs it has been found that satisfactory results are obtained by heating the bulb prior to the application 20 of the coating to the bulb. In the apparatus shown and described herein, the same oven is used for preheating the bulb and for baking the same after the coating has been applied so that the baking temperature and the 25 preheating temperature are the same, preferably about 350° C. It will be understood, however, that if desirable, two ovens may be employed and that the preheating temperature may be about 350° C. or above and the 30 baking temperature may be about 350° C. or above.

Although any suitable coating composition may be employed, it has been found that the present method gives satisfactory results 35 when a coating is provided containing sodium silicate, a filler such as Kaolin and a pigment with a suitable amount of water mixed in a ball mill until a homogeneous mixture is obtained. A mixture of this character is well known in the lamp coating art 40 and is more fully set forth in Patent 1,581,766.

In practicing the present method, bulbs or blanks are fed to the holders until the first 45 bulb is intermittently moved to a position in operative relation to the spraying mechanism 16. At the spraying station, the nozzle 26 is moved into and out from the bulb to deposit a layer of spray material on the interior surface of the bulb, which operation is 50 more clearly shown in Figs. 4 to 6. As will be noted, the nozzle 26 travels through a path at an angle to the longitudinal axis of the bulb. It is obvious, however, that the nozzle 55 26 may be moved through a predetermined path and the bulb may be held at an angle, in which case, the spray nozzle 26 might, for example, be moved horizontally. The result of this operation would, however, 60 be the same as moving the nozzle as above set forth.

The spraying of the interior surface of a hollow body such as a lamp bulb is a difficult and exacting operation. With the present 65 apparatus the nozzle 26 is moved into the

neck 55 until adjacent to a point as indicated by the dotted line 56 at which time the spray gun is operated to project a fan or conical shaped discharge 57 of finely divided material. Thus the spray is produced 70 within the article. The spray gun nozzle is then moved along the path indicated by the dotted line 58 which path has been chosen so as to keep the concentrated portion 59 of the spray as far from the surface wall 60 receiving the spray as is possible. The distance of the nozzle with relation to the said wall is limited by the dimensions of the bulb. 75

The importance of heating the bulb prior 80 to spraying will be appreciated for the reason that the spray must not run when it is applied to the bulb, but must be in such condition as to readily adhere to the surface and cover the same. When coating the outside surface of a bulb, the distance between the 85 bulb and the spray nozzle may be relatively long, thus the particles may be comparatively dry before reaching the bulb. The combination of the sprayed material applied within and to a wall of a heated bulb is an 90 important step in the present method.

As the gun moves into the bulb, the bulb is rotated at relatively high speed, thus causing an impingement or deposit of the spray material over the interior surface of the bulb. 95 Inasmuch as the bulb is rotated about its axis indicated by the dotted line 61, the upper end or tip 62 of the bulb will be in the dead center of rotation and rotate at relatively low speed as compared with the adjacent wall of the bulb. 100

As the spray gun moves into the bulb, the enlarged portion of the bulb will receive a certain amount of spray material owing to the length of time to which the wall of the 105 bulb is subjected to the discharge of spray. It has been found that in order to obtain a uniform layer of sprayed material upon the inside surface of the bulb, the comparatively dense portion 63 which may be termed the 110 main body thereof, should be moved so that this main body of spray does not reach the top portion 62 of the bulb. The spray gun is, therefore, moved until the main body of the spray is discharged adjacent to a point 115 on the dead center of rotation of the bulb so that the free or roving particles of spray which are projected from the main body will be deposited upon the upper wall of the bulb to produce a layer which, by reason of the 120 relatively long time period the upper wall is exposed to the roving particles of spray will produce a layer of material upon the upper wall equal in density and thickness to the deposit upon the adjacent wall or the remainder of the interior surface of the bulb. 125

In producing a sprayed lamp bulb, the thickness of the coating may be determined by the character of the material used or by the number of reciprocal movements or 130

passes of the spray nozzle within the bulb. If a light coating is to be obtained, it may only be necessary to move the spray nozzle into and out from the bulb, or if a heavier 5 coating is desired, the spray nozzle may be moved back and forth several times within the bulb.

It will be noted that the present method of 10 coating involves the bodily manipulation of a discharge of spray within the body to be sprayed. This makes it possible to properly cover the wall of the object such as a lamp which has a surface of undulatory form in longitudinal cross-section.

15 As illustrated in the drawings, the nozzle is shown as movable into and out from the bulb in such manner that the spray nozzle is held as far from the surface to be sprayed as practical. In practicing the present method, 20 it has also been found that good results are obtained by moving the nozzle into the bulb through a path in accordance with the contour of the surface to be coated. By this manner of manipulating the nozzle, the outlet 25 or discharge orifice of the nozzle may be maintained a uniform distance from the bulb.

As hereinbefore mentioned, it has been found that the degree of the density of the 30 coating may be controlled by the number of movements or passes of the nozzle into and out from the bulb and that the rate of speed of rotation of the bulb may be varied so that the surface to be coated will be exposed to the spray for a longer or shorter period.

35 It has further been found that when utilizing the preheating step it is possible to dispense with the final baking step. The bulb when preheated acts to dehydrate the applied 40 coating and by leaving out the final baking step the operation of coating is expedited and a greater quantity of bulbs may be coated in a given time period than has heretofore been possible.

45 By producing the spray after the nozzle has entered the bulb, it is possible to avoid a deposit of sprayed material upon the neck of the bulb. This is an advantage since after 50 the bulb has been sprayed it is necessary to perform what is termed a sealing-in operation. This operation consists in fusing the neck of the bulb to another lamp part termed a mount which latter part includes the filament and supporting structure. The sealing-in 55 operation necessitates the heating of the bulb neck until the same becomes plastic. If a deposit of another material such as a coating is applied to the bulb neck, the operation of heating is more difficult, since the coating absorbs heat and, therefore, makes it 60 difficult to properly melt the glass and fuse the bulb neck to the lamp mount.

When employing the present apparatus to 65 discharge a coating material containing sodium silicate, a nozzle is employed which discharges the sprayed material at an angle to

the body of the spray gun or at a predetermined angle. This angle must be maintained if a uniform layer is to be applied. It has been found, however, that the fine particles of the sprayed material become lodged between the air outlet orifice 32 of the spray nozzle and the tip 31 thereof and that these particles build up to such a degree as to offer an obstruction and change the angle at which the spray is projected. It will be evident 70 that if during operation, the angle of the spray is changed, the accuracy of operation is affected since a greater or lesser amount of spray will be deposited upon the upper surface of the bulb. The character of the sodium silicate coating composition is such that the building up of material upon the spray nozzle offers a considerable detriment to continuous and effective results.

75 The present invention, however, provides means for maintaining the nozzle free from an accumulation of material which means consists in the use of a nozzle associated with a source of steam supply to project a jet of steam 65 against the nozzle tip. A steam nozzle 80 may be positioned so as to direct discharged steam against the spray nozzle tip to clean the same after each movement of the nozzle from a bulb after a spraying operation.

85 By this method, the spray nozzle enters the bulb for each operation in such condition as to leave it free to operate for the discharge 90 of the spray at the predetermined angle. It has been found that with the present composition of coating using sodium silicate, that the moisture of the steam combined with its heat and the velocity with which it is projected from a nozzle, serves to cut the sodium silicate and keep the nozzle clean. It 95 is, of course, obvious that any other fluid may be employed as moist hot air or fluid of such character as to serve to remove the particular composition used for the coating. 100 Inasmuch as the jet of fluid is projected against the nozzle after each operation of the same for a coating of a bulb, air projected at high velocity will serve to remove any 105 particles of composition should they adhere too firmly to the nozzle. The use of steam, 110 however, not only dislodges the particles and by reason of the moisture affects a more complete removal of any material that may become deposited upon the nozzle tip or between the tip and the air outlet orifice.

115 The present method and apparatus not only serves to coat the interior surface of bulbs in an effective and efficient manner to produce a layer of uniform density and thickness, but by reason of the present method, the lamp bulbs may be coated at the high 120 rate of speed required in connection with other lamp making operations, whereby coated lamps may be produced at a minimum 125 cost.

Although a preferred embodiment of apparatus for practicing the present method is shown, it is to be understood that modifications may be made therein as well as variations in the method without departing from the spirit and scope of the invention as set forth in the appended claims.

What is claimed is:

1. An apparatus for depositing a layer of a light diffusing material upon the inner surface of a lamp bulb which comprises mechanism having a spray discharge orifice for light diffusing material, means for moving said mechanism into and out from said bulb and means for preventing an accumulation of spray material adjacent to said orifice.
2. An apparatus for depositing a coating of light diffusing material upon the inner wall of a lamp bulb which comprises a spray nozzle having a conduit for spray material and an outlet orifice for directing a spray of material at an angle to the longitudinal axis of said conduit, means for moving said nozzle into and out from said bulb and means for preventing accumulation of sprayed material adjacent to said outlet to maintain the discharge material at the required angle.
3. An apparatus for spraying a light diffusing material on the interior surface of a transparent hollow body of light transmitting material having a constricted neck portion and an enlarged body portion, comprising a spray gun having an extension for conducting spray material, a nozzle at the free end of said extension, means for moving said extension to cause said nozzle to travel into said body through a path intersecting the longitudinal axis of said body, means for causing a discharge of spray material at a predetermined point in the path of travel of said nozzle and means for rotating said body about said axis.
4. An apparatus for spraying a light diffusing material on the interior surface of a transparent hollow body of light transmitting material having a constricted mouth portion and an enlarged body portion, comprising a spray gun having an extension for conducting coating material, a nozzle at the free end of said extension, means for moving said extension to cause said nozzle to travel through a path so as to dispose the nozzle adjacent to one side of said body, means for actuating said gun to cause a discharge of sprayed material against the opposite side of said body and means for rotating said body about its longitudinal axis during the discharge of sprayed material.
5. An apparatus for coating the interior surface of a lamp bulb having a constricted neck with a light diffusing material, comprising means for heating the bulb, a spray nozzle having a spray outlet orifice, means for moving said nozzle into said bulb through a path intersecting the longitudinal axis of

said bulb to position the nozzle outlet orifice at one side of said bulb, means for causing a spray discharge against the opposite side of said bulb and means for rotating said bulb about said axis.

6. An apparatus for coating the interior surface of a lamp bulb having a constricted neck portion with a deposit of light diffusing material of uniform density, comprising a spray discharge nozzle having an outlet orifice, means for moving said nozzle through said neck portion to a position adjacent to one side of said bulb, means for causing a spray discharge against the opposite side of said bulb, means for rotating said bulb about its longitudinal axis, means for heating the bulb so that the coating material will pass through a heated environment and become partially dry before deposit upon said bulb and will completely dry upon striking the heated bulb to give a smooth uniform non-flowing layer.

In testimony whereof, we have hereunto subscribed our names this 8th day of December, 1927.
